UNITED STATES PATENT OFFICE

CLEMENS KUHLMANN, OF RATIBOR, GERMANY, ASSIGNOR TO SIEMENS PLANIAWERKE AKTIENGESELLSCHAFT FÜR KOHLEFABRIKATE, OF BERLIN-LICHTENBERG, GERMANY, A CORPORATION OF GERMANY

ELECTRODE JOINT

Application filed June 7, 1928, Serial No. 283,727, and in Germany July 2, 1927.

This invention relates to a method of connecting electrodes by means of which the stump of an old electrode is united with a new electrode for avoiding loss of material.

5 It has already been proposed to unite electrodes in such a manner that the electrodes to be connected are provided at their ends with similar threads for the reception of a separate nipple. For connecting the two 10 electrodes the nipple is screwed into one of the threaded holes and the new electrode is screwed on to the projecting half of the nipple. Such nipples have been made either of the same material as the electrodes or, in 15 order to reduce the resistance at the joint, they have been made of more conductive material, such as graphite or metal, or carbon electrodes have had metal cast into them. This method of connection has many draw- 20 backs and for this reason it has been proposed to turn off the electrodes at one end and to provide them with a conical thread, which fits in a corresponding thread in the other electrode. In the case of burned elec- 25 trodes it is very difficult to cut threads in them owing to their hardness and the wast- age in turning tools and diamonds being very heavy.

It has been found that the cutting of 30 threads can be entirely eliminated if the electrodes are provided at one end with a spigot only, which fits accurately into a corresponding hole in the other electrode, and that the electrodes prepared in this manner are 35 united by applying electrode cement to the spigot and the corresponding hole, the electrodes being thereupon united in a suitable manner for instance by turning them with respect to one another or by pressing them 40 together. The spigot may be made of any shape, for instance cylindrical or conical, or the spigot may be four-sided, either conical or straight. Conical spigots have been 45 found to be particularly suitable for the purpose. It has also been found to be of ad- vantage to provide the electrode at the place where it has a socket corresponding to the shape of the spigot with one or more holes 50 for allowing the air and any superfluous cement to escape through the holes. Both the

spigot and the socket may readily be made when the electrode is in the green state, i. e. before it has been burned, and any subsequent tooling, when the carbon is in the burned state can be easily carried out with- 55 out the use of turning tools or diamonds by means of grinding discs. A further advan- tage of the new method consists in this that with it electrodes of rectangular cross-sec- 60 tion can easily be joined without any danger of the joined electrodes canting. In order to prevent the joined electrodes sliding with respect to one another the part forming the joint may be provided at one or more places with holes, pins of metal or carbon being 65 inserted in the said holes, which when cemented in prevent the electrodes coming apart. This securing of the joint is gener- 70 ally necessary as otherwise there is a danger of the joint not being able to withstand the great pull acting on it in the case of heavy 75 electrodes.

It has also been found that the connection between the two electrodes can be secured in a still simpler manner by providing both 75 the spigot and the socket with one or more peripheral grooves into which a refractory cement can be poured. The cement is intro- 80 duced through one or more lateral holes drilled into the electrode having the socket. For cementing the electrodes together any 85 suitable cement may be used. A paste con- sisting of tar and carbon, which hardens at a relatively low heat, has been found to be very suitable.

In the accompanying drawing two con- structional examples of the electrode connec- 90 tion according to the invention are shown.

In Fig. 1 one electrode *a* has a conical spigot *b* which fits accurately into the corre- 90 sponding socket in the other electrode *c*. The latter is half bored through at the place *d* for allowing the air and the superfluous cement to escape. The electrode joint has a further hole *e* extending through the walls 95 of the socket and through the spigot *b*. It serves for the reception of pins of metal or carbon, the said pins extending through the entire joint or only being in- 100 serted from either side until they extend in-

to the spigot. The holes need only be a few millimetres in diameter and any number of such holes may be provided. In Fig. 2 one electrode *a* has a spigot *b* at its end which fits accurately into the corresponding socket in the other electrode *c*. Around the spigot *b* a peripheral groove *g* is formed by turning or milling, which corresponds to a similar groove *g*₁ milled in the socket. Into this groove a refractory cement is poured or forced through the hole *f*, filling the grooves *g* and *g*₁ and thereby forming a solid ring which secures the spigot in the socket so that it cannot slip out. The hole *d* acts as a vent for the air or the superfluous cement when the two electrodes are pressed together.

What I claim is:

For carrying out the method of uniting the stump of an old electrode to a new electrode in electric furnaces requiring a continuous feed of the electrodes into the furnace to make up for the electrode material consumed in the furnace, the combination of carbon electrodes having a spigot at one end and a socket at the other end forming a counterpart of said spigot and grooves in the walls of said socket and spigot, with cement interposed between said socket and spigot so as to cover the entire engaging surfaces of the spigot and socket and cement passed into said grooves, as and for the purposes set forth.

In testimony whereof I have signed my name to this specification.

CLEMENS KUHLMANN.
